UNITED STATES PATENT OFFICE.

WILLIAM S. McMANUS, OF CHESTER, PENNSYLVANIA.

BALL FOR TUBE-WELDING MANDRELS.

SPECIFICATION forming part of Letters Patent No. 398,638, dated February 26, 1889.

Application filed December 10, 1888. Serial No. 293,151. (No model.)

To all whom it may concern:

Be it known that I, WILLIAM S. McMANUS, a citizen of the United States, residing in Chester, in the county of Delaware and State 5 of Pennsylvania, have invented a new and useful Improvement in Balls or Mandrels for the Manufacture of Pipes, Tubes, &c., which improvement is fully set forth in the following specification and accompanying drawings.

10 The object of my invention is the construction of a ball or mandrel employed in the manufacture of metal tubes and pipes, the same being formed of an integral body rendered elastic, whereby the tubes or pipes are 15 prevented from sticking on the ball while in use.

Figures 1 and 3 represent side elevations of balls or mandrels embodying my invention. Figs. 2 and 4 represent end views thereof, respectively. Fig. 5 represents a section, on a reduced scale, of a pipe and a ball or mandrel in operative position therein as embodying my invention. Fig. 6 represents a longitudinal section of the ball or mandrel. Fig. 5. 25 Similar letters of reference indicate corresponding parts in the several figures.

Referring to the drawings, A designates a ball or mandrel for the manufacture of wrought-metal tubes and pipes, the same being of the form of a hollow shell, having a connecting core or neck, B, integral therewith, with an opening to receive the rod, which parts, excepting the feature of my invention applied thereto, are of well-known construction.

35 In the wall of the shell, Figs. 1 and 2, at opposite places, are longitudinally-extending slots C, which extend to the neck B, and in Figs. 3 and 4 a single slot is shown, the same 40 extending through the shell and core to the opening of the latter. In either case the continuity of the circumference of the shell is broken, while the core remains connected with the shell, it being seen that the slots render

the shell elastic, so that it is caused to yield 45 when subjected to pressure.

The ball may be formed with the slot or slots in the process of casting the same, or said slot or slots may be produced after the casting operation by a suitable cutting tool, 50 implement, or machine.

In the operation of making a tube or pipe the same passes over the ball, as usual. Should said tube or pipe stick on the ball, or vice versa, while passing through the rolls, the 55 pressure on the ball will cause the latter to spring inwardly or yield sufficiently to reduce the strain on the contiguous parts of the tube or pipe and ball, and thus allow the pipe to pass over the ball, as is evident. 60

I am aware that it is not new to make a ball or mandrel of separated parts connected by bolts or screws and springs; and I disclaim the same. By my construction I dispense with said bolts and springs and produce a stronger 65 and more serviceable article, and have therefore made an improvement in the art, it being evident that I do not limit myself to the location and number of the slots or grooves C, nor to the length or depth thereof. 70

Having thus described my invention, what I claim as new, and desire to secure by Letters Patent, is—

1. A ball for the purpose set forth, formed of an integral hollow body having the continuity of its peripheral wall broken by a longitudinally-extending slot or slots, substantially as described. 75

2. A ball for the purpose set forth, consisting of an integral hollow body with an interior neck and slot or slots breaking the peripheral continuity of said integral body, substantially as described. 80

WILLIAM S. McMANUS.
